UNITED STATES PATENT OFFICE.

FRANK E. BAKER, OF SYRACUSE, NEW YORK, ASSIGNOR TO CHAPIN-SKELTON CORPORATION, OF SYRACUSE, NEW YORK, A CORPORATION OF NEW YORK.

VALVE FOR GARMENT-PRESSING MACHINES.

Application filed April 23, 1925. Serial No. 25,258.

This invention relates to a garment pressing machine of the kind set forth in my pending application No. 754,630 filed Dec. 8, 1924, in that it refers more particularly to 5 the use of a single valve for controlling the supply and withdrawal of steam and moisture to and from the garment immediately preceding and following the pressing operation and while the garment is still in the 10 machine.

These machines are used more extensively by tailors, dry cleaners, clothing manufacturers and launderers for cleaning, sterilizing and shaping various articles of wearing 15 apparel which are usually brought to the machine in a dry condition and the common practice is to first apply a sufficient amount of moisture preferably steam to the garment in the machine for sterilizing and cleaning 20 purposes and also to render the garment sufficiently pliable for shaping under pressure of the pressing elements.

In the most modern machines suitable 25 means is provided for withdrawing the steam and moisture from the garment immediately following the steam and pressing operations and while the garment is still in the machine to prevent escape of steam into the room and also to free the garment from 30 moisture before removing it from the machine, all of which has the desirable effect of fixing the shape of the garment and greatly increasing the output of the work accomplished by a single machine and at the same 35 time permits the garments to be stacked as in the manufacture of clothing without liability of moulding, or, the garment may be put on and worn immediately following the pressing operation.

40 In the steam and moisture removing device heretofore employed it has been necessary to use two or more valves, one for controlling the application of steam to the garment and another for effecting a withdrawal 45 of steam and moisture from the garment and the main object of my present invention is to accomplish both these results through the operation of a single valve but in a different manner than that set forth in my pending 50 application above referred to.

For example, in the pending application referred to these two effects are produced by the operation of a single slide valve, which,

while highly efficient in accomplishing desired results applicant has found that a poppet valve constructed in the manner shown in the present application is more efficient, particularly in reducing the liability of leakages of steam and the specific object of this invention is to provide a poppet valve construction adjustable to one position for supplying the steam to the garment and to another position for withdrawing the steam from the garment thus permitting the single steam inlet to the valve to function for both 65 purposes.

Other objects and uses relating to specific parts of the device will be brought out in the following description.

In the drawings:

Figure 1 is a side elevation of a device for supplying and withdrawing steam moisture to and from one of the pressing elements, in this instance, the buck, shown in section.

Figures 2, 3 and 4 are horizontal sectional views taken on line 2—2, Figure 1, showing the valve in different positions for cutting off the steam supply and exhaust to and from the garment as in Figure 2, for admitting steam to the garment and cutting off the exhaust as in Figure 3 and for cutting off the steam supply to the garment and opening the exhaust as in Figure 4.

Figure 5 is an enlarged transverse vertical sectional view taken on line 5—5, Figure 1.

In order that the operation of my invention may be clearly understood I have shown the lower pressing element or buck —A— of a garment pressing machine of the kind set forth in my pending application Serial No. 25,259, filed April 23, 1925, said buck being provided with a steam chamber —a— for heating purposes and with a separate distributing chamber —a'— opening thru restricted passages —a''— through the top of the buck for supplying steam to the garment which is supported upon the upper face of the buck during the pressing operation.

The heating chamber —a— and distributing chamber —a'— are respectively connected by separate pipes —1— and —2— to separate ports —1'— and —2'— of a valve case —3—, the port —1'— being connected by a pipe —4— to any suitable source of

steam supply and forms a connecting passage between the supply pipe —4— and pipe —1— leading to the heating chamber —a— for maintaining a continuous supply of live steam to said chamber for heating the buck and also affords a means for supplying steam to the distributing chamber —a'— in a manner presently described.

The valve chamber —3— is also provided with a valve chamber —5— having a reduced extension —5'— adapted to receive a valve —6— having an enlarged head —6'— movable in the larger portion of the chamber —5— and reduced portion —6''— in the reduced extension —5'—, said valve being slidable endwise in the chamber —5— and is provided with a stem —7— extending axially through a gland —8— for connection with a suitable operating member —7'— Figure 1, in one end of the valve case —3—.

The opposite end of said valve chamber is provided with an exhaust port —9— connected to a waste pipe —10— for carrying away the steam and moisture which may be exhausted from the garment and also from the buck —a— in a manner presently described.

The valve case —3— is also provided with an annular steam chamber —11— surrounding the reduced portion of the valve —6— and communicating with the port —1'— and, therefore, in open communication with the source of steam supply thru the pipe —4— and in open communication with the heating chamber —a— thru the pipe —1—.

The annular steam chamber —11— is connected to the enlarged portion of the valve chamber —5— through restricted passages —12— which are normally closed by the enlarged portion —6'— of the valve —6— as shown in Figure 1 to prevent the passage of steam into the valve chamber when the valve is in its normally closed position and to permit the passage of steam from said annular chamber —11— to the valve chamber when the valve —6— is opened to either of the positions shown in Figures 3 and 4.

The reduced portion —6''— of the valve —6— is provided with a peripheral groove or steam passage —13— extending from the inner face of the enlarged portion —6'— of the valve toward the outlet port —9— a distance somewhat greater than the distance —55— between the port —2'— and enlarged portion of the valve chamber —5— so that when the valve is slightly opened from the position shown in Figure 2 to the position shown in Figure 3, the passage —13— will still retain communication with the port —2'— for connecting said port to the chamber —5— and thereby to allow steam to pass from said chamber to the distributing chamber —a'— through the pipe —2—, said passage —13— terminating in an annular

groove —13'— in the periphery of the reduced portion —6''— to produce more or less of a steam pressure balance around the valve particularly when the valve is adjusted to the position shown in Figure 3.

The end —14— of the valve farthest from the stem —7— is further reduced in diameter and is provided with a central lengthwise passage —15— extending axially toward the enlarged end —6'— and provided at its inner end with a branch radial passage —15'— opening through the periphery of the reduced portion —6''— at a point between the opposite ends of the lengthwise passage —13— for connecting the passage —15— to the chamber —5— when the valve is opened to the position shown in Figure 3 at which time the valve will have closed communication between the passage 13 and port —2'— and will have open communication between the chamber —5— and exhaust port —9— to allow the steam to pass through the branch —15'— and thence through the central passage —15— into the waste pipe —10— for drawing the moisture and steam away from the garment and distributing chamber —a'— thru the pipe —2— and port —2'—.

In other words, the reduced portion of the valve with the passages —15— and —15'— therein constitutes what may be termed an injector nozzle cooperating with the port —2'— when the valve is full open for directing steam from the chamber —5— through the nozzle and into the waste pipe —10— for creating suction in the port —2'— and thereby exhausting the steam and moisture from the distributing chamber —a'— of the buck and garment resting thereon thru the pipe —2— and discharging such steam and moisture thru the port —2'— and thence into the waste pipe —10— when the valve is adjusted to its full open position as shown in Figure 4.

The valve has three positions of adjustment, a closed position as shown in Figure 2, a partially open position as shown in Figure 3 for admitting steam to the garment and a full open position as shown in Figure 4 for withdrawing steam from the garment.

Operation.

Assuming that the pipe —4— is connected to the source of steam supply then under all adjustments of the valve, the steam will pass directly thru the pipe —1— to the heating chamber —a— for heating the buck —A— and inasmuch as the annular chamber —11— in the valve case —3— is in direct communication with and forms a continuation of the pipes —1— and —4—, it is evident that the live steam will also be present in said annular chamber —11— and its restricted passages —12— which latter are ar-

ranged about the axis of the valve —6— and terminate at the seat for the enlarged end —6'— of the valve.

It, therefore, follows that when the valve 5 is closed as shown in Figure 2 it will close the restricted passages —12— and thereby cut off communication between the annular passage —11— and chamber —5— thereby preventing the passage of steam thru the 10 passage —13— to the distributing chamber of the buck thru the port —2'— and pipe —2—.

Now, if, in pressing a garment on the buck it is desired to apply steam to said 15 garment for moistening and sterilizing purposes the valve —6— will be partially opened to the position shown in Figure 3 thereby withdrawing the enlarged portion —6'— from its seat to open the passages 20 —12— and thereby permit the passage of steam from the chamber —11— to the chamber —5— and thence thru the lengthwise passage —13—, port —2'— and pipe —2— to the distributing chamber —a'— where it 25 is applied to the garment thru the restricted passage —a''—, it being understood that this sterilizing and moistening operation is preferably performed while the pressing elements are in their pressing positions upon 30 the garment and that the partial opening of the valve for supplying the moisture to the garment is only for an instant depending somewhat upon the quality of the fabric.

Immediately following this steaming and 35 pressing operation the valve may be further opened to the position shown in Figure 4 or from a position at the exhaust side of the port —2'— to a position at the opposite side thereby cutting off communication between 40 the port —2'— and passage —13— and still maintaining communication between the chambers —11— and —5— thru the restricted passages —12— at the same time registering the branch passage —15'— with 45 the chamber —5— for permitting the steam to pass from said chamber thru the branch —15'— and thence thru the passage —15— of the nozzle —14— into the waste pipe —5— and beyond the port —2'—.

50 In this full open position of the valve the escape of the live steam thru the passage

—15— into the waste pipe —10— produces a high degree of suction in the port —2'—, pipe —2— and distributing chamber —a'— for withdrawing the steam from said distributing chamber and from the previously moistened garment which then rests upon the upper face of the buck thereby effecting a quick and complete drying of the garment so that it may be put on and worn immediately following the steaming and pressing operation or if the machine is used for pressing clothes in a clothing manufacturing concern the clothes may be stacked in the usual manner without liability of molding or wrinkling, it being understood that this high degree of suction causes an almost instantaneous drying of the garment which in turn produces a more effective setting and permanency of the shape produced by the pressing 70 elements when removed from the machine following the steam, pressing and drying operations, all of which are practically instantaneous and greatly increases the output 75 of the machine in addition to the greatly increased efficiency in its work upon the garment.

What I claim is:

In a valve mechanism, a valve case having a steam chamber provided with an inlet port, 80 an exhaust port and an additional port, means for supplying steam to the steam chamber through the inlet port and an ejector nozzle movable in the valve case and projecting into the exhaust port across the 85 adjacent port, said nozzle having means when in one position for closing the inlet port and with additional means when adjusted to another position for connecting the inlet port to the additional port and simultaneously cutting off communication between the inlet port and the exhaust port, said nozzle being adjustable to a third position and provided with means when in that position 90 for receiving steam from the inlet port and discharging it through the exhaust port past the additional port and with additional means for opening communication between 95 said additional port and the exhaust port.

In witness whereof I have hereunto set 100 my hand this 14th day of April, 1925.

FRANK E. BAKER.
